UNITED STATES PATENT OFFICE

CLAUDE H. DANIELS, OF NEWTON CENTER, MASSACHUSETTS

BOOT OR SHOE AND METHOD OF MAKING SAME

Application filed October 10, 1930. Serial No. 487,822.

My present invention relates to boots and shoes, and includes a novel method of manufacturing same, the present invention being an improvement on the invention illustrated, 5 described and claimed in my prior Patent, No. 1,772,340, dated August 5, 1930.

Briefly stated, the essence of my invention consists in perforating a plurality of rows of apertures through predetermined portions of shoe upper materials, and thereafter weaving strips separate from the upper material through predetermined rows of apertures. The word "aperture" as utilized in the present application signifies a hole, 15 as distinguished from a slot or a slit. By the utilization of apertures, rather than slits, I am enabled to create innumerable designs, patterns, and ornamentations, which would not be capable of achievement with mere slits. The presence of the apertures enables the weaving or threading of a plurality of the separate strips through a single aperture, to thus increase the capacity for variations 25 of designs possible in my novel shoe.

In carrying out the present invention I preferably utilize two upper pieces, such as a vamp and vamp lining, both of which are preferably preformed of identical size. Leather is preferably utilized as the outer 30 vamp piece, and for the lining I utilize a sheet of material of greater toughness and less stretch than the outside vamp piece. I then coat the entire contacting face of either one or both of said vamp pieces, and subject 35 the same to a pressure operation, which will effectually unite the two vamp pieces into a substantially integral vamp. I preferably also utilize heat during the pressing operation to more fully insure the union of the 40 said two vamp pieces.

As the next step in my novel method, I then subject the entire vamp, in its united condition, to a perforating operation, punching a plurality of substantially equi-sized and substantially equi-spaced apertures throughout substantially the entire area of 45 said vamp. This perforating of the entire area of the vamp would have a weakening effect on the vamp materials, were it not for the fact that I utilize a lining of considerable

toughness and little stretch, said lining, nevertheless, being of desired flexibility. Thus, although the vamp is perforated throughout its entire extent, it may be pulled over and lasted without materially 55 distorting the upper materials or the perforations or apertures. This lack of distortion is also due to the fact that the individual perforations are of small individual size, and their aggregate area will, therefore, not 60 materially weaken the vamp or upper materials.

As the next step in my novel process I weave, through predetermined apertures or rows of apertures, strips of material separate 65 from the upper materials, the presence of the apertures enabling these strips to cross each other through a single aperture, or enable an individual strip to follow different lines of direction through the rows of 70 apertures without distortion or bulking of the upper materials.

After the strips are woven to a predetermined design, I apply a row of stitching around the marginal portion of the upper 75 materials to unite the strips to the upper materials at this point and prevent loosening thereof during wear as well as during the lasting and other shoe manufacturing operations.

I may vary the process above briefly described by perforating merely the outside vamp piece, weaving the same in the manner above mentioned, and then adhesively uniting a vamp lining to the woven outside vamp 85 piece, applying stitching around the marginal edge of the united vamp sections to secure the woven strips in place as above described. For many types of design this latter method will be equally satisfactory, and the same is 90 within the scope of the present invention, as will be readily understood.

After the operations just described, the completion of the shoe is preferably carried out in the manner illustrated, described, and 95 claimed in my said prior patent, and reference is hereby made to said patent.

In the present shoe, I may insert a toe stiffener between the two vamp layers, subjecting said toe stiffener to the same steps as 100

above outlined, and weaving the toe portion of the vamp in the same manner as the balance thereof.

I believe that the steps of the process of shoe manufacture above briefly outlined are novel, as well as the resulting shoe constructed thereby, and have, therefore, claimed the same in this application.

The above and other objects and features of the invention, details of construction, and advantages, will be hereinafter more fully pointed out, described and claimed.

Referring to the drawings, illustrating a preferred embodiment of the present invention,

Fig. 1 is a plan view of the two vamp pieces assembled and coated, with one layer turned back to illustrate the position of the toe stiffener;

Fig. 2 is a side elevation of the united vamp during the pressure operation;

Fig. 3 is a fragmentary longitudinal sectional view illustrating the perforating operation;

Fig. 4 is a plan view of the perforated vamp, illustrating also the method of weaving the separate strips and the stitching thereof;

Fig. 5 is an enlarged cross sectional view on the line 5—5 of Fig. 4;

Fig. 6 is an enlarged cross sectional view on the line 6—6 of Fig. 4;

Fig. 7 is a perspective view of the completed shoe;

Fig. 8 is a plan view of the modified vamp structure above described; and

Fig. 9 is an enlarged cross sectional view on the line 9—9 of Fig. 8.

Referring now to the drawings, for a particular description of the invention, and the method of carrying out the same, my novel vamp comprises two layers of material, 1 and 2, these layers being preferably cut to identical size before uniting. The layer 1 is preferably of leather, although it is within the purview of my invention to utilize other materials if desired. The layer 2 is preferably of a material different from the layer 1. There are several well known textile materials suitable for the lining layer 2, said materials being much tougher and less elastic than the leather utilized in the outside vamp layer 1. The contacting faces of the layers 1 and 2 are then coated with a suitable adhesive, as at 3, 3, either one or both of said surfaces being thus treated.

If desired, also, a layer 4 may be inserted between the two layers 1 and 2 at their toe portion, this layer 4 being of a suitable material to provide a toe stiffener in the completed shoe. The surfaces of this stiffener layer 4 may be coated with a suitable adhesive, as illustrated at 5, if desired, although the adhesive 3 on the layers 1 or 2 may be sufficient for this purpose.

The adhered layers 1, 2 and 4 are then subjected to a pressure operation, as between the two presser members 6 in Fig. 2. These presser members 6 are also preferably heated, although this is not essential. The pressing operation will firmly and integrally unite the layers 1, 2 and 4, or the layers 1 and 2, if the stiffener layer 4 is not utilized.

Subsequent to the pressing operation I then subject the united vamp materials to a perforating operation, the die 7 operating in conjunction with the anvil 8 to perforate a mass of fine apertures or perforations 9 completely through the united vamp materials, as well as through the stiffener layer 4. As clearly illustrated in Fig. 4, this mass of perforations extends over the entire area of the vamp materials, even to the edges thereof.

As the next step in my novel process I then weave strips 30 through predetermined rows of apertures 9, these apertures permitting the passing therethrough of a plurality of said strips at predetermined points, as illustrated at 31, without distortion of the upper materials. As clearly illustrated in Figs. 5 and 6, the strips 30 are woven completely through both the layers 1 and 2.

The design illustrated in Fig. 4 is for illustrative purposes only, as it will be appreciated and understood that an infinite variation of designs is possible when utilizing the perforated vamp or upper material as a base.

After all the desired strips have been woven, I apply a row of stitching 32 around the peripheral margin of the layers 1 and 2, with the exception of the throat portion thereof, as none of the strips 30 extend into the throat portion. This stitching 32 will firmly secure the ends of the strips 30 to the upper material, and the projecting ends of said strips, as illustrated in dotted lines at 33, may then be severed flush with the edge of the upper material, although this severing operation may take place before the stitching 32 is applied, if desired.

A collar 10 is then united to the vamp along the entire throat margin thereof by a single row of stitching 11. This collar is of sufficient width so that a portion thereof will extend beyond the throat margin, as clearly illustrated in Fig. 5.

As the next step, the outside quarter 12 is united to the collar 10 by a row of stitching 13, subsequent to which the quarter lining 14 is united to the vamp layers 1 and 2, and collar 10, and, throughout a portion of its extent to the outside quarter layer 12, by a row of stitching 15, this stitching extending through the quarter lining 14, outside quarter 12, vamp layers 1 and 2, and collar 10, and at the point illustrated by the numeral 34, the stitching 15 passes through the strip 16 of the quarter lining, vamp layers 1 and 2, and collar 10.

Subsequent thereto, a beading 17 is af-

- fixed to the free edge of the collar 10 by a row of stitching 18, another row of stitching 19 uniting the quarter lining 14 and its strip 16 to the collar 10 and beading 17. Thereafter 5 the thus assembled upper materials will be assembled on a last, and completed in any desired manner, whether welt or McKay, the outsole 20 and heel 21 being applied in the usual manner.
- 10 The completed shoe manufactured according to this process will be light, and yet strong and durable. Also, because of the perforation of the entire vamp, thorough ventilation will be provided, as well as admitting the 15 sunlight directly to the foot of the wearer. Because of the combination of the two layers 1 and 2 of the vamp materials, the said vamp will not be distorted during pulling over or lasting, the individual size of the 20 perforations 9 being so small that the aggregate thereof has no material weakening effect on the vamp. The vamp, at the toe portion is still further strengthened by the presence of the stiffener layer 4, which will also assist 25 in retaining the shape of the shoe during wear.
- The presence of the strips 30 further increases the strength of the upper material, as will be readily understood.
- 30 In Figs. 8 and 9 I have illustrated a slight modification, wherein the outer vamp piece 35 is perforated in the same manner as illustrated in Fig. 4, whereupon strips 36 are woven therethrough. From a glance at Fig. 8 it 35 will be instantly apparent that the strip designated as 36 is angled or bent at 37, and is then woven through another row of apertures 38, proceeding to the aperture of the layer 35 at an angle to the original line of 40 direction of the strip 36.
- The design shown in Fig. 8 is merely illustrative of the vast range of design features capable of achievement in my novel shoe and by my novel process.
- 45 The apertures 38 permit of the bending of the strips 36 without distortion of the upper materials, and subsequent to the weaving the lining layer 39 is adhesively secured to the woven layer 35, a toe stiffener 40 being interposed therebetween if desired. Thereupon a 50 row of stitching 41 is applied through the woven layer 35 and lining 39, although this stitching operation may be performed before application of the lining 39, if desired. The 55 collar 10 is applied by stitching 11 in the same manner as illustrated in Fig. 4. A vamp or other shoe upper portion constructed according to this phase of my invention is rugged, strong, and durable, and will not be distorted by any of the steps of shoe manufac- 60 ture.
- While I have necessarily described my present invention somewhat in detail, it will be appreciated that I may vary the size, shape, 65 and arrangement of parts within reasonably wide limits without departing from the spirit of the invention.
- My invention is further described and defined in the form of claims as follows:
1. The improved process of shoe manufac- 70 ture, which includes the steps of adhesively uniting a vamp and vamp lining, simultaneously perforating a plurality of apertures completely through both said vamp and said vamp lining, and weaving strips separate 75 from said layers through predetermined apertures of both the vamp and the vamp lining, whereby the latter are positively held together independently of the adhesive.
2. The improved process of boot or shoe 80 manufacture which includes the steps of superimposing an upper section and lining therefor one upon the other, simultaneously perforating alined openings completely through said upper section and lining, and 85 weaving strips separate from said upper section and lining through predetermined openings of both the upper section and the lining to positively secure the upper section and lining together.
3. The improved method of boot or shoe 90 manufacture which includes the steps of superimposing a vamp and a toe stiffener one upon the other, forming alined openings through said vamp and said toe stiffener, and 95 weaving strips through said openings to positively secure the vamp and the toe stiffener together.
4. The improved process of boot or shoe 100 manufacture which includes the steps of arranging a vamp, a toe stiffener and a vamp lining in superimposed relation, forming alined openings through said vamp, toe stiffener and vamp lining, and weaving strips 105 through said openings to positively secure the vamp, the toe stiffener and the vamp lining together.
5. A boot or shoe including a vamp and a toe stiffener having alined openings formed therethrough, and strips woven through said 110 openings serving to positively secure the vamp and the toe stiffener together.
6. A boot or shoe including a vamp, a toe stiffener and a vamp lining disposed in superimposed relation and having openings formed therethrough, and strips woven through said 115 openings serving to positively secure the vamp, the toe stiffener and the vamp lining together.
- In testimony whereof, I have signed my 120 name to this specification.
- CLAUDE H. DANIELS.
